METAL AND WOOD FRAME
Filed Jan. 20, 1928

UNITED STATES PATENT OFFICE

ISAAC A. BAUM, OF CHICAGO, ILLINOIS

METAL AND WOOD FRAME

Application filed January 20, 1928. Serial No. 248,157.

My invention relates to buildings and particularly to novel framing for wall openings therein.

An object of my invention is to provide a composite frame structure composed of metal and wood and so arranged that the utmost rigidity is assured. This result is secured by utilizing a channel shaped frame structure corresponding to a rough buck, the metal structure serving as a support for one or more wood blocks rigidly secured to the support, the wood blocks serving as a mounting for the usual jamb or other framing for the opening.

15 The advantage of the illustrated construction is that the wall and opening may be completed with the assurance that there will be no cracks in the plaster at the junction of the frame with the wall such as commonly occur due to shrinkage or warping of a wood buck, yet permitting the use of wood trim without requiring special fastening means therefor.

In ordinary practice the wood rough bucks 25 cannot be erected with accuracy and even though they are so erected, the tendency to shrinkage and buckling is apparent in a short time. It is, therefore, necessary to accurately assemble the finished wood frame or jamb 30 before it is erected and attached through wedging or blocking, this blocking taking up the variation between the sides of the rough bucks and the finished frame.

With the steel frame or buck such as disclosed herein the situation is quite different. The steel frame members are made very accurately and so erected without any skill on the part of the workman. The wood blocks within the steel frame are retained without 40 any possibility of buckling or non-alignment. Therefore, the finished frame can be erected as three loose pieces nailed directly to the wood blocks which saves a substantial amount of time in assembling the pieces before installation. Furthermore this avoids the necessity for an attempt to ship the finished frame in assembled condition and permits the contractor to buy the finished lumber for shipment to the job with a minimum bulk 45 and damage in transportation.

The invention will be more readily understood by referring to the accompanying drawings, in which—

Fig. 1 is a sectional view through a wall constructed in accordance with my invention, 55 the parts being shown in perspective;

Fig. 2 is a sectional view on the line 2—2 of Fig. 3, and

Fig. 3 is a sectional view on the line 3—3 of Fig. 2. 60

Fig. 4 is a perspective view of the frame member of my invention.

In the drawings I have illustrated a metallic frame member comprising a web 10 and side flanges 11. Ears 12 are struck out at 65 intervals from the web of the channel and bent backwardly substantially in line with the flanges 11. These ears serve as means for positioning the channel relative to the tile or other wall elements 13. As a means for anchoring the channel relative to the tile, I may provide the looped member 14 having hook ends 15 that project into the openings formed by striking out the ears and lie back 70 of the web 10 of the channel.

The vertical and horizontal members of the metal frame may be joined at their ends in any suitable manner, preferably in the manner illustrated in my co-pending application, Serial 248,156 filed of even date here-with. 75

At intervals in the length of the channel frame members, I mount wood blocks 16 best shown in Figs. 2 and 3 same being held in place by means of nails 17 projecting through the flanges 11 of the channel. To the wood blocks I secure a wood element 18 in the nature of a sub-buck, the width of the board 18 being substantially exactly that of the thickness of the finished wall including the plaster 19. The sub-buck therefore 80 serves as a plaster ground. A jamb 20 is positioned by means of the usual wedges 21, and molding 22 of any suitable shape is applied to the face of the wood members 18, 20 and overlie the joint with the plaster. 90

A construction such as described may be easily and cheaply applied with the assurance of full rigidity and permanency of the frame relative to the plaster and yet permit- 100

ting unlimited selection of the decorative wood trim.

The form and arrangement of the parts may be varied within limits without departure from the spirit of my invention.

I claim:

1. In framing for wall openings the combination of a metal channel, the flanges of which project into the opening, ears struck 10 out of the web of the channel and projecting rearwardly in line with said flanges and serving as means for positioning the channel relative to a wall, a wood block fixed in the channel, a sub-buck secured to the block 15 and serving as a plaster ground, a casing element secured to the sub-buck, and molding overlying the edges of the casing element and the sub-buck and secured thereto.
2. In framing for wall openings, the combination of a metal channel, the flanges of 20 which project into the opening, ears struck out of the web of the channel and projecting rearwardly in line with said flanges and serving as means for positioning the channel relative to a wall, a plurality of wood blocks 25 fixed in the channel in vertically spaced relation, a sub-buck secured to the block and serving as a plaster ground, a casing element secured to the sub-buck, and molding overlying the edges of the casing element and the sub-buck and secured thereto.
3. In framing for wall openings, the combination of a metal channel, the flanges of 30 which project into the opening, ears struck out of the web of the channel and projecting rearwardly in line with said flanges and serving as means for positioning the channel relative to a wall, a wood block in the channel, fastening means projecting through 35 the flanges of the channel into the block, a sub-buck secured to the block and of substantially the exact width of the finished plaster wall whereby it is adapted to act as a plaster ground, and a jamb mounted on 40 said sub-buck.
4. In framing for wall openings the combination of a metal channel, the flanges of 45 which project into the opening, ears struck out of the web of the channel and projecting rearwardly in line with said flanges and serving as means for positioning the channel relative to a wall, a wall anchor in the form of a loop having hook ends adapted to enter the openings caused by striking out said ears, 50 wood blocks fixed in said channel in vertically spaced relation, a sub-buck secured to the blocks and acting as a plaster ground, and a jamb secured to the sub-buck.

In testimony whereof I have affixed my
60 signature.

ISAAC A. BAUM.
